TOY TRUCK

Leslie Perhacs, Jr., Topanga, Calif., assignor to Cragstan
Industries, Inc., New York, N.Y., a corporation of New
York

Filed Mar. 12, 1969, Ser. No. 16,204

Term of patent 14 years

Int. Cl. D21—02

U.S. Cl. D34—15

FIG. 1

FIGURE 1 is a perspective view of my new design for a toy truck;

FIGURE 2 is a side elevational view showing the side opposite that shown in FIGURE 1; and

FIGURE 3 is a rear elevational view thereof:

I claim:

The ornamental design for a toy truck, as shown.
